COME-ALONG FOR METAL DRAWING MACHINES

Filed Sept. 12, 1927

UNITED STATES PATENT OFFICE

GEORGE E. BARNHART, OF PASADENA, CALIFORNIA

COME ALONG FOR METAL-DRAWING MACHINES

Application filed September 12, 1927. Serial No. 219,162.

This invention relates to the art of forming metal objects, such as tubular or rod-like products by the operation of drawing the same through suitable dies or forming devices, being more particularly a novel come-along or gripping head arranged to impart a positive movement of the work through the dies or forming devices.

It is one of the principal objects of my invention to produce a come-along of simple form and construction, effective to firmly grip thin walled material and so arranged as to, by simple operation of the return movement of the come-along, quickly release such material.

Another object of my invention is to provide a come-along having gripping or wedge blocks interiorly surfaced to enter the surface of the material or stock to a predetermined distance and thereby prevent slippage of the stock during the working operation.

Another object of my invention is to provide a come-along of simple form, arranged to grip material or stock in the form of a tube without pointing the tube as ordinarily done.

Other objects and advantages appear hereinafter from the following description and accompanying drawings.

Referring to the drawings, which are for illustrative purposes only,

Fig. 1 is a sectional elevation of a come-along embodying a form of my invention.

Fig. 2 is a plan view, partly in section, of the come-along shown in Fig. 1.

Fig. 3 is a cross-sectional view on line 3—3 of Fig. 2.

Fig. 4 is a cross-sectional view on line 4—4 of Fig. 2.

Fig. 5 is an enlarged longitudinal sectional view through one of the wedge blocks, showing the engagement of the same with the stock.

Fig. 6 is a plan view partly in section of a modified form of my invention, and

Fig. 7 is a cross sectional view on line 7—7 of Fig. 6.

Referring particularly to the embodiment of my invention shown in the accompanying drawings, 11 designates a carriage, the for-

ward end of which is forked or slotted as indicated at 12 to receive a follower 13, such follower consisting of a plate or bar slotted as indicated at 14 to receive bolts 15, which extend through the forked end of the carriage 11, such mounting of the follower on the carriage 11 allowing a certain limited longitudinal movement of the follower in the carriage. The follower is provided with a downwardly extending finger or abutment 16, which is designed to engage between the links of a chain 17, the finger 16 engaging the pins or rivets 18 of the chain. This chain 17 may be of any desired form, preferably of the endless chain type, adapted to be driven by sprockets from a power source, as will be understood by those skilled in the art. The rear end of the carriage 11 is slotted horizontally, as indicated at 20, to receive a cam plate 21, such cam plate being pivotally attached to the carriage by means of a headed bolt or pin 22, retained in place by means of a cotter pin 23.

The cam plate 21 is provided with two diagonally disposed cam slots 24, such slots being diagonally disposed with relation to the longitudinal axis of the come-along, and rearwardly converging as illustrated in Fig. 2.

25 designates two sets of bell crank levers, there being one such lever of each set disposed above and the other lever being disposed below the cam plate 21, as shown in Fig. 1. Each lever 25 comprises a long arm 26 and a short arm 27, the long arm of each set of levers being pivotally connected to a headed pin or pivotal member 28, which extends through slots 24 in the cam plate 21. The levers 25 are pivotally mounted by means of pins or pivot members 30 in a recess 31 formed in the rear end of a head 32 and spaced apart by spacing collars 33. The short arm 27 of each lever terminates in a rounded head 34, adapted to engage the forward ends of stock or material gripping wedges 35. These stock gripping wedges are mounted in and engageable with a circular seat 36, formed in a central opening in the head 32, the inner surface or face of such opening being tapered away from the seat 36, as indicated at 37. 100

The head 32 is supported in the machine by means of angle bars 41, and is directed through its travel by means of guide blocks or members 40, which slide between longitudinal channels or members 42 of such frame. The short arms 27 of the levers 25 are beveled, as indicated at 44 in Fig. 3, so as to permit clearance for the stock, should the same extend forwardly between such 5 levers. The stock gripping members 35 consist, in the form shown, of four sections which together form substantially a frusto conical gripping member, each having its outer face tapered inwardly and rearwardly, 10 as shown at 45, to engage the seat 36 in the head 32, as shown in Figs. 1 and 2.

These gripping members 35 are provided on their inner face with a series of ribs 48 designed to bite into the stock for the purpose of more securely gripping the same between the gripping members. These members 45 are also provided with channels 49 arranged to receive spring members 50, having a tendency to expand such gripping 20 members.

The come-along, in the form just described, operates in the following manner. It being understood that the chain 17 has been engaged by the finger 16 on the follower 13; the 30 follower resting upon the chain as shown in Fig. 1, the follower is moved forwardly as indicated by the arrow in Fig. 1 until the rear bolt 15 engages the rear end of the slot 14, whereupon the carriage is moved forwardly with the follower and the pull of the carriage on the cam plate 21 causes the long arms 26 of the bell crank levers 25 to move inwardly in the position shown in Fig. 2. The further forward pulling movement of 35 the carriage exerts a further inward movement of the arms 26, thereby causing pressure of the short arms 27 against the forward end of the wedging members 35. Such wedging members, due to their co-operative relation 40 with the seat 36, are wedged tightly against the stock which, in the present instance, is shown as a tube 51, until the ribs bite into the stock, as shown in Fig. 5, thereby firmly securing the stock in the come-along. When 45 used for drawing thin tubes, as indicated at 51, a short mandrel 52 is preferably inserted in the end of the tube and the stock engaged between such mandrel and the straight inner faces of the wedging members, as shown in 50 Fig. 5, after the ribs have engaged the stock as just described. Further forward movement of the carriage draws the entire come-along forwardly, together with the stock engaged by the gripping members. After the 55 stock has traveled through the dies, generally indicated diagrammatically at 52, the movement of the gripping chain 17 is stopped and either reversed or the follower is disengaged from the chain. In either case the follower, 60 being moved rearwardly, the arms 26 are

opened, due to the engagement of the pins 28 in the cam slots 24 in the plate 21. Such outward movement of the arms 26 relieves pressure of the short arms against the stock engaging means, thereby permitting an opening or expanding of the members of the stock gripping means by disengagement of such members from the seat 36 in the head 32 and removal of the work therefrom. By making the seat 36 in the head 32 short in length and the opening beveled away from such seat, as heretofore described, it will be understood that the wedging members may more freely be moved from engagement with the stock than in the case where a long engagement is had between such seat and the stock engaging members.

It is to be understood that the straight inner faces of the wedges 35 between the ribs 48 are designed to engage the stock and at the same time limit the depth of the bite of the ribs into the stock. By so constructing the wedges a contact with the stock by the wedges 35 is maintained throughout the length of the wedges except at the grooves 49.

As to the size of the ribs 48, such ribs are proportioned so that the area of the ribs, multiplied by the pressure exerted over the ribs, is less than the elastic limit of the stock.

In the form of come-along shown in Figs. 6 and 7, the head 60 receives a plurality of wedge members 61 which are engaged at their forward ends by levers 62 pivoted thereto, the outer ends of such levers being connected by links 63 with a carriage 64, which is provided with a finger 65 to engage the drive chain 66. The carriage 64 is recessed as shown at 67 to permit free movement of the come-along rearwardly, at the end of the drawing operation, the recess 67 allowing clearance for the stock indicated at 70.

I claim as my invention:

1. A come-along for advancing work through dies comprising: a head apertured to form a circular tapered seat; a plurality of stock gripping members having their outer faces engageable on said seat; a plurality of levers pivotally mounted on said head engaging said gripping members; and lever engaging means independent of said head for advancing said head and imparting gripping movement to said stock gripping members, said levers comprising draft means for said gripping members.

2. A come-along for advancing work through dies comprising: a head apertured to form a tapered seat; a plurality of stock gripping members having their outer faces engageable on said seat; a plurality of levers pivotally mounted on said head engaging said gripping members and adapted to act as draft means for said gripping members; and lever engaging means independent of said head for advancing said head and imparting gripping movement to said stock gripping members.

members, said lever engaging means consisting of a cam plate and pins on said levers engaging said cam plate.

3. A come-along for advancing work through dies comprising: a head apertured to form a tapered seat; a plurality of stock gripping members having their outer faces engageable on said seat; a plurality of levers pivotally mounted on said head engaging said gripping members; and lever engaging means for advancing said head and imparting gripping movement to said stock gripping members, said lever engaging means consisting of a plate having rearwardly converging cam slots formed therein and means on said levers engaging in said cam slots.

4. In combination with a driven member, a come-along for advancing work through dies comprising: a head apertured to form a seat; a plurality of tapered stock gripping members engaging said seat; a plurality of levers pivotally mounted on said head engaging said stock gripping members; a plate having cam slots therein; means on said levers engaging said cam slots; supporting means for said plate; and means for releasably connecting said supporting means to said driven member.

5. In a come-along for advancing work through dies: a head apertured to form a seat; a plurality of segmental frustro-conical gripping members engaging said seat; and means pivotally mounted on said head and engaging said gripping members for simultaneously advancing said head and applying positive pressure to said gripping members in a direction opposed to said advance for forcing said gripping members against said seat.

40 6. In a come-along for advancing work through dies: a head apertured to form a seat; a plurality of segmental frustro-conical gripping members engaging said seat; means pivotally mounted on said head and engaging said gripping members for simultaneously advancing said head and applying positive pressure to said gripping members in a direction opposed to said advance for forcing said gripping members against said seat; and means for yieldingly expanding said gripping members.

7. In combination with a driven member, a support, a head slideable on said support apertured to form a seat, wedge-shaped stock gripping members on said seat, bell crank levers pivotally mounted on said head, a short arm on said levers engaging said gripping member, a plate having cam slots therein, long arms on said levers, pins on said long arms engaging said cam slots, and means for advancing said plate.

8. In a come-along for advancing material through dies, a head having an aperture therein forming a seat, a plurality of segmental tapered gripping members in said

head engaging said seat, and a plurality of ribs on the gripping face of said gripping members, said gripping members having corresponding recesses therein and spring members in said recesses to expand the gripping members.

9. A come-along comprising a head apertured to form a circular seat, a plurality of gripping members extending into said aperture in engagement with said seat, and a plurality of draft members pivotally mounted on said head having gripping member engaging portions engaging the ends of said gripping members.

10. A come-along comprising a head apertured to form a circular seat, a plurality of gripping members extending into said aperture in engagement with said seat, and a plurality of draft members pivotally mounted on said head having gripping member engaging portions engaging the ends of said gripping members, said gripping members having recesses formed therein and split ring elastic members in said recesses for yieldingly expanding the gripping members.

In testimony whereof, I have hereunto set my hand at Los Angeles, California, this 25th day of August, 1927.

GEORGE E. BARNHART.
